FUSE IN LEAD-IN OF INCANDESCENT
LAMP FILAMENT

George H. Burnett, Cleveland Heights, Ohio, assignor to
General Electric Company, a corporation of New York
Filed Sept. 19, 1962, Ser. No. 224,737
3 Claims. (Cl. 315—73)

This invention relates in general to electric incandescent lamps and similar devices, and more particularly to an electric incandescent lamp of the self-contained reflector type having an internal fuse.

Incandescent lamps, especially the high wattage types, require a fuse since at the end of life an arc may form between the burnt ends of the filament and result in violent failure. As the arc starts to form, more current is drawn through the lamp, whereby the fuse burns out and violent failure is prevented. Since it is inconvenient for the user to replace an external fuse as well as the lamp after the lamp burns out, it is desirable to incorporate the fuse into the lamp itself. The incorporation of a fusible material into the lead-in wires of an incandescent internal reflector lamp could result in a substantial weakening of the support for the filament.

Therefore, it is an object of this invention to provide a fuse within the lamp itself which does not substantially weaken the filament support. It is a further object to provide a structure which may easily and economically be assembled.

Briefly stated, in accordance with the invention at least one of the lead-in wires of the lamp is provided with a fusible material section which is surrounded by a closely fitting hollow sleeve or standard of insulating material fused in the thimble supporting the lead-in wire, thereby adequately supporting the filament.

Further objects and advantages of the invention will appear from the following detailed description of the preferred embodiment of the invention and from the accompanying drawing wherein:

FIG. 1 is a perspective view, certain parts broken away, of an electric incandescent lamp having an internal fuse comprising the invention;

FIG. 2 is a sectional view of the lamp; and

FIG. 3 is a fragmentary sectional view on an enlarged scale of the lead wire provided with the fusible material section.

Referring to the drawing, the invention is there illustrated as embodied in an electric incandescent lamp of the self-contained reflector type such as described and claimed in U.S. Patent 2,148,314, Wright, issued Feb. 21, 1939, and assigned to the assignee of the present invention. The lamp comprises a bulb or envelope 1 consisting of a preformed pressed glass reflector section 2 sealed around its periphery to a preformed pressed glass cover section 3. The interior surface of the reflector section 2 is of suitable light-concentrating shape such as paraboloidal, for instance, and it is covered with a metallic coating 4 of aluminum or silver to constitute a reflecting surface. Mounted on the reflector section 2, exteriorly thereof and at the apex of said section, is a base structure 5. The base structure 5 may be of the type described and claimed in U.S. Patent 2,272,512, Cotman et al., dated February 10, 1942, and comprising a pair of metallic lugs (not shown) suitably secured as by soldering to metallic cups or thimbles 7 having their edges sunk and embedded in the glass of the reflector section 2 around openings 8 therein, the cups or thimbles thus hermetically closing said openings 8. The envelope 1 is exhausted and filled with a suitable inert gas through an exhaust tube 9 attached to the reflector section 2 at its apex. After the gas filling is introduced into the lamp envelope,

2

the exhaust tube 9 is tipped off, as indicated at 10, to hermetically seal the envelope.

Mounted within the envelope 1 and supported therein from the metal thimbles 7 is a mount structure comprising an electric energy translation element or filament 11 disposed between and connected to a pair of rigid lead-in wires or conductors 12 and 13 of suitable material, such as nickel or iron. The lead-in conductors 12 and 13 are rigidly secured at their outer ends to the metal thimbles 7, as by soldering or by brazing, and they may extend straight through the opening 8 in the reflector section into the interior of, and in more or less parallel relation to one another and preferably in a plane parallel to and including the axis of the reflector section 2. The lead-in conductors 12 and 13 are held in rigid spaced relation by an insulating bridge or cross bar member comprising a glass rod 14 extending between and secured to the lead-in conductors by short fastening wires 15 which may be spot-welded to the lead-in conductors. Inwardly of the envelope 1, the lead-in conductors 13 are offset away from each other to form offset outer end portions 16 to which the ends of the filament 12 are connected.

The filament 12 is constituted of tungsten wire, and in the particular case illustrated comprises a linear coiled-coil disposed transversely to the reflector axis in a position in definite optical relation to the focus of the reflecting surface 4, preferably symmetrically about the reflector focus. As shown, the filament may be a high wattage type, for example 650 watts on 240 volts, and is therefore rather heavy and long. To support the coiled-coil filament 12 intermediate the ends attached to lead-in conductor offset portions 16, a brace wire 17 embedded in the glass rod 14 is attached to one of the center turns of the coiled-coil filament to secure and maintain the intermediate portion of the filament in correct position with respect to the focus of the reflector surface 4. A screen 18 supported from lead-in conductor 12 by the member 19 is provided to prevent the tungsten vapors given off by the filament in operation from condensing on the envelope 1 and causing bulb blackening. It will be understood that the lamp as shown is designed for operation with the axis of the reflector and the axis of the filament in a horizontal position and with the screen 18 positioned above the filament 12.

With a lamp of this type having a high wattage filament, it is necessary to fuse the lamp so that violent failures at the end of lamp life do not occur. This has been customarily done by some external fusing means. The lamp, as shown, in accordance with this invention, has an internal fuse 20 (FIG. 3) butt-welded between portions 13a and 13b of lead wire 13. The fuse 20 may be any suitable fusible material of proper dimensions so as to fail when the peak inrush of current at end of lamp life occurs. Surrounding the composite structure of lead wire part 13a, fuse 20 and lead wire 13b is a hollow standard or sleeve 21 of insulating material which may be, for example, a glass tube having an inside diameter slightly larger than the outside diameter of the lead wire sections 13a and 13b. The outer end of standard 21 is fused or embedded in the solder joint 22 of the thimble 7 for the lead wire 13.

It has been found that it is unnecessary to secure standard 21 at its inner end to lead wire section 13b and therefore it will be noted in FIG. 3 that the inner end of standard 21 surrounds and is spaced slightly from conductor 13b. The spacing between the inner end of standard 21 and conductor 13b may be defined as a slip-fit spacing, that is, a spacing such that in assembly the standard 21 may be easily inserted over the composite structure of lead wire 13a, fuse 20 and lead wire 13b. This construction provides lead-in wire 13 with adequate

strength to support the filament 11 because the fuse section 20 has adequate strength in longitudinal compression and tension, the main weakness of the composite structure being against bending stresses. Since the mount structure is supported on one side by a rigid conductor wire 12 fused to the other thimble 7 bending stresses applied by the weight of the filament and screen or by external forces, place these stresses on conductor 13b which displaces it within standard 21. The inner end of standard 21 is sufficiently close to lead wire portion 13b so that any canting of conductor 13 is prevented by the inner end of standard 21, and the filament and screen is maintained in its proper position. Thus, it will be noted that there is provided a lamp of the reflector type having a high wattage filament which is provided with an internal fuse which does not weaken the support necessary for the filament and other auxiliary equipment within the lamp.

The above construction has the additional advantage of being easily and economically manufactured on standard reflector lamp equipment since the only additional operation to be performed on the actual assembly machine is the insertion of the standard 21 around lead wire 13, the mount structure for the lamp being provided with the fusible section 20 in one of the conductor wires prior to assembly into the envelope. The mount structure having the fusible section therein and the standard 21 surrounding the lead wire may then be aligned in the reflector section 2 of the lamp with the conductor wires 12 and 13 within respective thimbles 7. Then, as is customary, the solder pellet may be placed in the thimble 7 and heat applied thereto. The solder pellet may be, for example, of the type disclosed in U.S. Patent 2,745,742, issued May 15, 1956, which comprises a sintered powder mass of brass solder and borate glass flux. The melting of the solder pellet secures the conductor lead-in wires, as is conventional, and additionally in the same single operation, secures the standard 21 to the thimble as well. Thus, the new and advantageous structure may be assembled with a minimum of difficulty and cost.

While the invention has been disclosed by way of its preferred embodiment, it will be understood that it may be widely modified within the spirit and scope of the appended claims.

What is desired to be secured by Letters Patent of the United States is:

1. An electric incandescent lamp comprising a sealed envelope having a base structure including a pair of

thimbles hermetically closing adjacent openings in a wall of said envelope, a pair of lead wires having outer end portions anchored in respective said thimbles and extending into the interior of said envelope, a filament supported by said lead wires, at least one of said lead wires having a fusible section adjacent its outer end and adjacent the associated thimble, and a hollow standard of insulating material closely surrounding the outer end portion of said one lead wire including said fusible section and having one end thereof extending from and anchored in the associated thimble.

2. An electric incandescent lamp comprising a sealed envelope having a base structure including a pair of thimbles hermetically closing adjacent openings in a wall of said envelope, a pair of lead wires having outer end portions anchored in respective said thimbles and extending into the interior of said envelope, a filament supported by said lead wires, at least one of said lead wires having a fusible section butt-welded between spaced portions of its outer end adjacent the associated thimble, a glass tube closely surrounding the spaced portions of said one lead wire and the interposed said fusible section and extending from within said associated thimble, and means securing the ends of said one lead wire and the glass tube to the said associated thimble.

3. An electric incandescent lamp comprising a sealed envelope having a base structure including a pair of thimbles hermetically closing adjacent openings in a wall of said envelope, a pair of lead wires having outer end portions anchored in respective said thimbles and extending into the interior of said envelope, a filament supported by said lead wires, at least one of said lead wires having a fusible section butt-welded between spaced portions of its outer end adjacent the associated thimble, a glass tube closely surrounding the spaced portions of said one lead wire and the interposed said fusible section and extending from within said associated thimble, and a quantity of fused solder securing the ends of said one lead wire and the glass tube to the said associated thimble.
